Primary Examiner — Rhea Shields(74) *Attorney, Agent, or Firm* — Sughrue Mion, PLLC(57) **CLAIM**

The ornamental design for a connector housing, as shown and described.

DESCRIPTION

FIG. 1 is a bottom view of the connector housing that we consider to be our invention;

FIG. 2 is a front elevation view thereof;

FIG. 3 is a left side view thereof;

FIG. 4 is a rear elevation view thereof;

FIG. 5 is a right side view thereof;

FIG. 6 is a top view thereof; and,

FIG. 7 is a perspective view thereof.

Broken lines are provided to show portions of the connector housing that are not being claimed, and thus form no part of the claimed design.

1 Claim, 7 Drawing Sheets(56)
